Des. 210,757
Patented Apr. 9, 1968

210,757

CERVICAL SPATULA

Raymond S. Michel, Portland, Oreg., assignor to United Medical Laboratories, Inc., Portland, Oreg., a corporation of Oregon

Filed June 23, 1967, Ser. No. 7,574

Term of patent 14 years

(Cl. D83—12)

FIGURE 1 is a side elevation of a cervical spatula embodying my new design, the opposite side is a mirror image of the side shown;

FIGURE 2 is a top plan view thereof, the undisclosed bottom portion is substantially the same in appearance as the top, except for the relative shape of the blade members as best illustrated in FIGURE 1;

FIGURE 3 is an enlarged end elevation as seen from the left of FIGURE 1; and

FIGURE 4 is an enlarged end elevation as seen from the right of FIGURE 1.

The crisscross pattern disclosed on the tip of the blade members in FIG. 1 is intended to represent surface ornamentation.

I claim:

The ornamental design for the cervical spatula, as shown and described.
